CABINET HAVING COMBINED SHELF AND SLIDABLE DOORS

Donald T. Houpt, Seattle, Wash., assignor to Boeing Airplane Company, a corporation of Delaware

Application March 17, 1945, Serial No. 583,223

8 Claims. (Cl. 312—189)

1

The door construction to which my invention relates is particularly suitable for use in kitchen cabinets, but it is readily adaptable to many other types of installations.

The doors are arranged in pairs and mounted to slide edgewise into overlapping disposition in which the inner door is almost completely covered by the outer door, though the doors are preferably of the same width.

A principal object of my invention is to provide a sliding door construction which will suspend the doors and guide their movement without the necessity of a fixed track engageable with the lower edges of the doors. The lower shelf of the cabinet closed by the doors may therefore be formed as a continuation of a work bench outside the cabinet without any projection or recess interrupting the unbroken continuity of such shelf and exterior bench.

In such an arrangement it is also an object to mount my cabinet doors inclined downwardly and inwardly to increase the width of the bench space exteriorly of the cabinet. The doors may be inclined to any degree, and they may be opened to add the lower shelf of the cabinet to the bench space to make a wide work area when desired.

A further important object of my invention is to provide hardware for such a door construction which is very simple to manufacture and easy to install, yet which will support the doors effectively and enable them to be removed from the cabinet openings by simple manipulation. In particular it is an object to support the inner door wholly from the cabinet structure and to support the outer door partially from the cabinet structure and partially from the inner door.

The principles of construction and operation embodied in the representative form of my invention shown in the drawings may be incorporated in structures varying considerably from that illustrated and particularly described hereafter.

Figure 1 is a front elevational view of a cabinet incorporating my door structure.

Figure 2 is a vertical sectional view through the door structure shown in Figure 1 taken along line 2—2 of that figure, and Figure 3 is a fragmentary sectional view of the door structure on line 3—3 of Figure 1.

My door structure may be employed in conjunction with cabinets having any number of shelves, the cabinet 1 shown in the drawing having a single intermediate shelf 10. When such cabinet is used in a kitchen its bottom shelf 11

2

and a work bench 12 exteriorly of the outer cabinet door 2 may form a continuous surface.

The outer door 2 and the inner door 20 as shown in Figure 1 are preferably substantially equal in width and extend from the bench 12 and lower shelf 11 of the cabinet to its top 13. When the outer door is slid over the inner door, or the latter door is slid behind the former, the shelf 11 forms additional work space behind the bench 12. Moreover such arrangement is very desirable for storage of an electric mixer, for example, because it can be slid through the cabinet doorway to a location behind the inner door 20 without being lifted. When this door is closed the mixer is covered. When the door is open, however, the mixer may be drawn outward onto the bench portion 12 again without the necessity of lifting it. The same technique may be used for other kitchen utensils to avoid lifting them.

20 To increase the width of the work bench space available outside the cabinet when the doors are closed, they may be inclined inwardly and downwardly so that their lower edges will be set a substantial distance behind their upper edges.

25 The supporting and guiding hardware for the doors need not be changed appreciably for different degrees of door inclination. Both doors are suspended, as distinguished from resting on their lower edges, but the suspension mechanism is not secured to or engaged with the upper edges of the doors. Conventional hanger mechanism usually is rather complicated and frequently does not restrain swinging of the doors unless their lower edges are guided by tracks.

30 In my door arrangement the inner door is supported independently of the outer door by rollers 21 engaging a track 14 secured to the outer edge of an intermediate shelf 10. The particular track shown is of channel shape, having a curved web portion and flanges of different widths. It is preferably made of metal, although it may be desirable to use some type of plastic or other material, or even a wooden ledge. The broader flange of such channel is secured to the shelf 10 edge while the edge of the narrower flange constitutes the track for the rollers. These rollers are secured to the inner face of the inner door by simple straps or brackets 22. Such a bracket is shown in Figure 2 as extending vertically upward from the roller, but a horizontal bracket 23 may be used alternatively, or for one roller while the other is supported by a vertical bracket. The entire weight of the inner door 20 is supported by the two rollers 21, one carried by each upright edge of the door.

The rollers 21 are secured to the inner door 20 at locations intermediate its top and bottom edges. The particular position of these rollers vertically is not of great importance, but it is preferred that they be disposed a substantial distance below the upper edge of the door. The upper door edge fits into a downwardly facing groove 15 near the outer edge of the cabinet top 13, the door edge 24 preferably being rabbeted to reduce the width of the groove required. When the door 20 is supported by its rollers 21 with its upper edge received in groove 15 it is restrained from swinging conjointly by the groove and by the rollers engaging the track, so that it can merely be slid edgewise.

The outer door 2 has a roller 21 secured to one of its edges by a strap or bracket 25 to dispose such roller in registry with track 14. The end of this strap may project forwardly past the edge of the door and beyond its exposed face to serve as a handle which may be grasped to slide the door. One upright edge of the door can therefore be supported by this track and roller engagement in the manner previously described in connection with the structure of door 20, but a roller cannot be located similarly on the opposite edge of door 2 because of the interference which would occur between its bracket and inner door 20 as the doors are moved relatively into overlapping relationship. This edge of the door is therefore supported from the inner door rather than from the cabinet structure.

For this purpose a roller 26, located behind the inner door 20, is supported from the outer door 2 by a strap or bracket 27 which extends from the rear side of the roller downwardly and forwardly beneath the lower edge of door 20, as shown best in Figure 2. The forward end of the strap is secured to the lower edge of the outer door to support the roller. This roller is engaged with a track 28 extending along the lower portion of the inner surface of door 20 and secured to it. Like track 14, track 28 is preferably of channel shape, having flange portions of unequal width. The wider flange portion is secured to the door and the edge of the narrower flange portion constitutes the track for roller 26. The upper edge of the outer door is likewise received in a groove 16 in the top 13 of the cabinet, parallel to groove 15. The upper edge 29 of door 2 is rabbeted so that the grooves 15 and 16 can be spaced apart a reasonable distance.

In the cabinet of Figure 1 the opening is shown as closed by only two sliding doors, but it will be evident that any number of doors may be employed, arranged in pairs, which doors may be of any desired width, and may close the opening of a cabinet of any height. Either the inner door 20 of each pair may be slid behind the outer door of its pair into the broken line position indicated in Figure 3, or the outer door may be slid over the inner door of its pair, to contract the width of the closure in either direction. If more than a single pair of doors are employed, the doors may all be pushed toward one end or the other of the cabinet opening until the doors of each pair overlap to the fullest extent and the several pairs of doors are in contact. When thus disposed the doors collectively occupy little more than half the total width of the cabinet opening.

To install my door structure it is only necessary to form in the top 13 of the cabinet the two grooves 15 and 16, and to secure the track 14 to an intermediate shelf. The remainder of the hardware is mounted on the doors themselves,

as previously discussed. When the doors are installed they will be in close face to face relationship, the supporting rollers of both doors being concealed from view.

5 In order to place the doors in operative position the inner and outer doors of each pair may first be assembled with each other; the roller 26 carried by the outer door engaging the track edge of the channel 28. Both doors will now together 10 be placed in the cabinet opening in overlapping relationship, and their upper edges 24 and 29 will be fitted into the respective grooves 15 and 16 of the cabinet top 13, and pushed edgewise upward as far as possible. The rollers 21 may now 15 be passed over track 14 and the doors allowed to move downward to engage such rollers with the track to support the doors. The doors are then ready to be slid into position for closing the opening. They may be removed from the cabinet 20 easily by following in reverse the sequence of the steps enumerated.

I claim as my invention:

1. A cabinet comprising a top, a bottom, a shelf substantially midway between its top and bottom and having its outer edge disposed inwardly of the outer edge of said cabinet top, a door extending substantially from said top to said bottom, and means interengaged between said door, the outer edge of said cabinet top, and the outer edge 25 of said shelf, operable to support said door in a position inwardly and downwardly inclined and to guide it for edgewise movement parallel to such outer shelf edge in such attitude, said means at the outer edge of said shelf carrying substantially 30 the entire weight of the door, and said means at the outer edge of said cabinet top guiding the upper edge of the door for such movement, and restraining the door against tilting.

2. A cabinet comprising a top having a groove 40 in its under side along the edge thereof, a bottom, a shelf intermediate said top and bottom and having its outer edge disposed inwardly of the groove in said top, a door extending substantially from said top to said bottom and having its upper edge engaged in the groove in said top, and means 45 interengaged between said door and the outer edge of said shelf, and operable to support said door, such groove and said interengaged means cooperating to maintain said door in a position inwardly and downwardly inclined generally parallel to a line joining such groove in said top and the outer edge of said shelf, and to guide said door for edgewise movement parallel to such outer shelf edge in such attitude.

55. 3. A cabinet comprising a top, two parallel guides at its under side along the outer edge thereof, a bottom, a shelf intermediate said top and bottom, an inner door extending substantially from said top to said bottom and having its upper edge engaged with the inner one of said 60 cabinet top guides, an outer door extending substantially from said top to said bottom and having its upper edge engaged with the outer one of said cabinet top guides, a track secured to the outer edge of said shelf, two rollers carried by opposite edges of said inner door, respectively, and bearing on said track to support said door for edgewise movement parallel to such outer shelf edge while the upper edge of the door is 65 guided by the inner one of said cabinet top guides, a roller carried by one edge of said outer door and bearing on said track, a track carried by the lower edge of said inner door at the inner side thereof, and a roller carried by said outer door at the bottom of its other edge and bearing 70

on said second track, to support such other edge of said outer door from said inner door while the upper edge of said outer door is guided by the outer one of said cabinet top guides for edgewise movement of said outer door relative to said inner door in a direction parallel to it.

4. A cabinet comprising a top having two parallel grooves in its under side along the outer edge thereof, a bottom, a shelf substantially midway between said top and bottom, an inner door extending substantially from said top to said bottom and having its upper edge engaged in the inner groove in said cabinet top, an outer door extending substantially from said top to said bottom and having its upper edge engaged in the outer groove in said cabinet top, a track secured to the outer edge of said shelf, two rollers carried by opposite edges of said inner door, respectively, and bearing on said track to support said door for edgewise movement parallel to such outer shelf edge while the upper edge of the door is guided by such inner cabinet top groove, a roller carried by one edge of said outer door and bearing on said track, a track carried by the lower edge of said inner door at the inner side thereof, and a roller carried by said outer door at the bottom of its other edge and bearing on said second track, to support such other edge of said outer door from said inner door while the upper edge of said outer door is guided by the outer groove in the cabinet top for edgewise movement of said outer door relative to said inner door in a direction parallel to it.

5. A cabinet comprising a top, two parallel guides at its under side along the outer edge thereof, a bottom, a shelf intermediate said top and bottom, an inner door extending substantially from said top to said bottom and having its upper edge engaged with the inner one of said cabinet top guides, an outer door extending substantially from said top to said bottom and having its upper edge engaged with the outer one of said cabinet top guides, two rollers carried by opposite edges of said inner door, respectively, and track means disposed along the outer edge of said shelf to support and guide said rollers for movement edgewise of the door parallel to such outer shelf edge while the upper edge of the door is guided by the inner one of said cabinet top guides, a roller carried by one edge of said outer door and supported by said means disposed along the outer edge of said shelf, a track carried by said inner door, and a roller carried by the other edge of said outer door and bearing on said track, to support such other edge of said outer door from said inner door while the upper edge of said outer door is guided by the outer one of said cabinet top guides for edgewise movement of said outer door relative to said inner door in a direction parallel to it.

6. A cabinet comprising a top, a bottom, a shelf intermediate its top and bottom, an inner door extending from said bottom to said top, means interengaged between said inner door, the outer

edge of said cabinet top and the outer edge of said shelf operable to guide said door for edgewise movement parallel to such outer shelf edge and to support its weight, respectively, an outer door, and means interengaged between said outer door and said inner door operable to support said outer door at least partially from said inner door for edgewise movement relative thereto in a direction parallel to it.

10 7. A door structure for a cabinet having a shelf intermediate its top and bottom, comprising a track adapted to be carried by the outer edge of the shelf, a door of a height to extend a substantial distance above and below such shelf, a roller carried by said door and bearing on said track to support said door for edgewise movement parallel to such outer shelf edge, an outer door of a height to extend a substantial distance above and below such shelf, a roller carried by one edge of said outer door and bearing on the track carried by the outer edge of the shelf, a track carried by the first door, and a roller carried by the other edge of said outer door and bearing on said track carried by the first door, for supporting said outer door partially from the shelf and partially from the first door for edgewise movement relative to the first door in a direction parallel to it.

15 8. A cabinet comprising a top, a bottom, a shelf intermediate said top and bottom, a door extending a substantial distance above and below said shelf, means interengaged between said door and said shelf and supporting a substantial portion of the weight of said door for edgewise movement parallel to the adjacent edge of said shelf, 30 means guiding the upper edge of the door during such movement, an outer door extending a substantial distance above and below said shelf, means interengaged between one edge of said outer door and said shelf, and means interengaged between the other edge of said outer door and the first door, for supporting said outer door partially from the shelf and partially from the first door for edgewise movement relative to the first door in a direction parallel to it.
